BLOW-OFF MUFFLER

John Webster Small and Aaron Grayson Dawson,
Richmond, Va., and Charles Walter Buffington,
Huntington, W. Va.

Application October 3, 1929, Serial No. 396,993

6 Claims. (Cl. 137—160)

The present invention relates generally to mufflers or silencers for steam blow-off pipes. More particularly the invention relates to that type of muffler which is adapted for connection to the blow-off valve of a locomotive steam engine and is operative, during the blow-off operation, to muffle the exhausted steam and to diffuse it so that there will be no intense blast or jet which, if directed downwardly, would disintegrate or damage the subjacent roadbed.

One object of the invention is to provide a muffler of the aforesaid type, which comprises a cylindrically shaped casing and embodies coacting muffling elements that are arranged and constructed in a novel manner and serve to effect an improved silencing or muffling action.

Another object of the invention is to provide a muffler of the abovementioned character, which comprises a tubular open ended exhaust member that is formed integrally with and projects radially from the cylindrically shaped casing and operates to form a laterally extending outlet duct for the steam.

A further object of the invention is to provide a muffler of the character under consideration, in which the laterally or radially extending exhaust member has formed in the bottom thereof rows of discharge openings and embodies a plurality of comparatively small deflectors which operate to break up the outflow of steam through the outlet duct and to direct the condensate and a major portion of the steam through the discharge openings.

A still further object of the invention is the provision of an auxiliary deflecting plate which is secured to the outer or distal part of the exhaust member and is bendable across the open end of the outlet duct to retard as desired the flow of steam through said duct and operates to direct downwardly the steam that is not discharged through the openings in the bottom part of the exhaust member.

Additionally, it is contemplated as one of the objects of the invention to provide a muffler for use in connection with a steam blow-off valve, which is generally of new and improved construction and may be manufactured more readily and economically than mufflers for a similar purpose now in use or heretofore proposed.

Other objects of the invention and the various advantages and characteristics of the present muffler construction will be apparent to those skilled in the art from a consideration of the following detailed description.

The invention consists in the several novel features hereinafter set forth and more particularly defined by the claims at the conclusion hereof.

In the drawing which accompanies and forms a part of this specification or disclosure and in which like numerals of reference denote corresponding parts throughout the several views:

Figure 1 is a vertical longitudinal sectional view of a muffler embodying the invention;

Figure 2 is a view partly in plan and partly in section; and

Figure 3 is a transverse section taken on the line 3—3 of Figure 1 and illustrating the arrangement of the discharge openings in the tubular exhaust member and the construction of the deflectors for directing the condensate and a portion of the steam through the aforesaid openings.

The invention is exemplified in a muffler which is designed primarily for use in connection with the blow-off valve of a locomotive steam engine and is adapted to be disposed beneath the steam boiler and to be connected to the blow-off valve by a pipe or similar connecting instrumentality 4. This muffler is formed of a one-piece casting and comprises a casing 5 which consists of a cylindrical side wall 6, a circular top 7 and a bottom 8. The central portion of the top 7 is extended upwardly to form an inlet nipple 9. This nipple has formed therein an internal screw-thread 10 for connection to an external thread 11 on the pipe or connecting instrumentality 4.

Housed or contained in the casing 5 is a spreader 11 which consists of a conical top 12 and an annular wall 13. Said wall 13 depends from and is formed integrally with the marginal part of the top 12. The spreader is positioned beneath and in concentric relation with the top 7 and is held in its operative position by webs 14. There are preferably four of the webs 14 and the latter are formed integrally with the casing and the spreader and serve to space the top 12 from the casing-top 7 and thereby form a chamber 15 into which the steam flows from the pipe 4. By virtue of the fact that the top 12 is of conical formation the steam entering the chamber 15 through the pipe 4 is deflected outwardly and against the upper portion of the cylindrical side wall 6. The annular wall 13 of the spreader 11 is spaced inwardly from the side wall 6 and forms with the latter a tubular passageway 16 into which the steam passes from the chamber 15.

The marginal part of the top 7, that is the part that is joined to the upper portion of the side wall 6 is curved outwards, as at 7a in order to guide or direct the steam downwardly into the tubular passageway 16 which is 55

formed by the walls 6 and 13. The central portion of spreader 11 is hollow.

Disposed beneath the annular wall 13 is a baffle ring 17. This ring is positioned substantially midway between the spreader 11 and the bottom 8 and operates to direct inwardly the steam that passes through the tubular passageway 16. The outer marginal portion of the baffle ring is formed integrally with the cylindrical side wall 6 of the casing. The inner marginal portion of the ring is curved upwardly, as at 18, so as to guide the steam upwardly into the hollow part of the spreader and against the under side of the top 12 for diffusing or muffling purposes. From the hollow part of the spreader, the steam flows downwardly through the central opening in the baffle ring 17 into a compartment 19 which is formed between the ring and the bottom 8 of the casing.

The muffler, in addition to the casing 5, comprises a tubular open ended exhaust member 20 which is formed integrally with the lower end of the cylindrical side wall 6 and projects radially therefrom. This member is rectangular in cross section and comprises a top wall 21, sides 22 and a bottom wall 23. The top wall 21 and the bottom wall 23 are coplanar with the baffle ring 17 and the bottom 8 respectively and form with the sides 22 a laterally extending outlet duct 24 which communicates with and receives steam from the compartment 19. The bottom wall 23 has formed therein transverse rows of elongated discharge openings 25. These openings are staggered or relatively offset and are inclined so as to extend toward the casing 5. A portion of the steam that flows through the duct 24 is directed into the openings 25 by a plurality of deflectors 26. These deflectors are formed integrally with the bottom wall 23 and are inclined toward the casing 5 similarly to the openings 26 in order to break up the outflow of steam through the duct 24 and guide the condensate and a portion of the steam into the openings. A characteristic and an advantage of utilizing deflectors of the type herein disclosed is that the steam is exhausted in a muffled and diffused condition, due to the fact that said deflectors operate to produce an irregular surface and effectively retard the flow of steam through the duct 24. The deflectors 26 are arranged directly above the discharge openings respectively and are coextensive with said openings. The side margins of the deflectors are joined to the bottom wall 23 by triangular-shaped side pieces 26a.

To retard additionally the flow of fluid through the duct 24, a deflecting plate 27 is provided. This plate is secured to the top wall 21 of the exhaust member and is adapted to be bent downwardly into an angular position so as to extend over the open end of the duct 24. In this position the steam is retarded and is directed downwardly upon exhaust thereof from the duct. By changing the angle of the plate relatively to the duct 24, the rate of flow of the steam may be controlled.

Vertically extending pads 28 are formed integrally with the outer face of the cylindrical side wall 6 and operate to reinforce the casing 5 and as anchors for attaching devices, such as bolts.

The operation of the muffler is as follows: When steam is discharged through the pipe 4, it passes downwardly into the compartment 15 and is directed outwardly by the conical formation of the spreader-top 12. From the compartment 15 the steam travels downwardly through the tubular passageway 16 which is formed between the cylindrical side wall 6 and the annular wall 13. From the passageway 16 the steam is directed inwardly

and upwardly by the baffle ring 17 and then flows downwardly into the compartment 19. From said compartment 19 the steam together with any condensate that may have been formed flows laterally through the duct 24 and is discharged through the openings 25 as a result of the action of the deflectors 26. In view of the fact that the spreader and baffle ring cooperate with the casing 5 to form a sinuous or serpentine conduit, the steam is effectively muffled and retarded with respect to its flow. The portion of the steam that is not deflected by the deflectors 26 flows through the open end of the exhaust member 20 and is directed downwardly by the auxiliary deflecting plate 27.

The muffler herein disclosed has proved in practice to be extremely efficient and may be manufactured readily and economically for the reason that all of the parts with the exception of the deflecting plate 27 are integral and capable of being formed from a one-piece casting.

Although the muffler has been described for use in connection with a blow-off valve of a locomotive steam engine, it is to be understood that it may be used equally as well in other capacities and with other fluids. It is also to be understood that the invention is not to be restricted to the details set forth, since these may be modified within the spirit and scope of the invention.

Having thus described the invention, what I claim as new and desire to secure by Letters Patent, is:

1. In a blow-off muffler of the character described, the combination of a vertically extending casing comprising a substantially flat top with a fluid inlet in the central portion thereof, a cylindrical side wall and an imperforate bottom, a conical spreader in the upper part of the casing arranged so that its apex portion underlies the inlet and the marginal portion thereof directs against the top portion of the side wall the fluid introduced into the casing through the inlet, and embodying a depending annular wall that forms with the cylindrical side wall an annular passageway through which the fluid flows downwardly from the upper part of the casing, a baffle ring disposed in the central part of the casing and joined to and projecting inwardly from the side wall of the casing, said ring being flat except for the inner marginal part thereof and the latter being inclined upwardly to direct the fluid so that it flows upwardly into the space within the depending annular wall where it strikes against the bottom of the spreader and then flows downwardly through the central hole or opening in the ring into the lower part of the casing and against the casing bottom, an open-ended tubular exhaust member connected to and projecting laterally from the bottom portion of the side wall of the casing and arranged to form an outlet duct whereby the fluid after flowing against the bottom of the casing is discharged laterally from the muffler.

2. A blow-off muffler embodying a one-piece, cast metal casing comprising a substantially flat top with a fluid inlet formed in the central portion thereof, a cylindrical side wall and an imperforate bottom, a conical spreader in the upper part of the casing arranged so that its apex portion underlies the inlet and the marginal portion thereof directs against the top portion of the side wall the fluid introduced into the casing through the inlet, and embodying a depending annular wall that forms with the cylindrical side wall an annular passageway through which the fluid flows downwardly from the upper part of the casing,

- webs for supporting the spreader extending between and formed integrally with the depending annular wall of the spreader and the side wall of the casing and operating to divide into sections the annular passageway, a baffle ring disposed in the central part of the casing and formed integrally with the side wall of the casing, said ring being flat except for the inner marginal part thereof and the latter being inclined upwardly to direct the fluid so that it flows upwardly into the space within the depending annular wall where it strikes against the bottom of the spreader and then flows downwardly through the central hole or opening in the ring into the lower part of the casing, and against the casing bottom, and an open-ended, tubular exhaust member of substantially rectangular cross section formed integrally with and projecting laterally from the bottom portion of the side wall of the casing and arranged so that the top and bottom walls thereof are substantially coplanar with the ring and casing bottom respectively and so as to form a lateral outlet duct whereby the fluid after flowing against the bottom of the casing is exhausted from the muffler.
3. In a blow-off muffler of the character described, the combination of a vertically extending, one-piece, cast metal casing having a fluid inlet in the upper part thereof and consisting of a top, a cylindrical side wall and an imperforate circular bottom, means in the casing operative to effect a primary muffling of the fluid introduced through the inlet and to direct the fluid into the lower part of the casing including a substantially horizontal baffle ring formed integrally with and projecting inwardly from the intermediate part of the side wall, an open-ended, tubular exhaust member of substantially rectangular cross section formed integrally with and projecting laterally from the lower part of the casing and arranged to form an outlet duct for the fluid and so that the top and bottom walls thereof are substantially coplanar with the ring and casing bottom respectively, and means for breaking up and effecting a secondary muffling of the fluid as it flows through the outlet duct and is discharged from the open end of the exhaust member.
- 50 4 In a blow-off muffler of the character described, the combination of a vertically extending casing having a fluid inlet at the upper part thereof and consisting of a top, a cylindrical side wall and an imperforate circular bottom, means in the casing operative to effect a primary muffling of the fluid introduced through the inlet and to direct the fluid into the lower part of the casing including a substantially horizontal baffle ring joined to and projecting inwardly from the intermediate part of the side wall, an open-ended, tubular exhaust member of substantially rectangular cross section connected to and projecting laterally from the lower part of the casing and arranged so as to form an outlet duct for the fluid and so that the top and bottom walls thereof are substantially coplanar with the ring and casing bottom respectively and the side walls extend substantially tangentially with respect to the casing side wall and are joined to the latter at diametrically opposite points, and means for breaking up and effecting a secondary muffling of the fluid as it flows through the outlet duct and is discharged from the open end of the exhaust member.
5. A blow-off muffler comprising a casing adapted to extend vertically and having a fluid inlet in the upper part thereof, coacting muffling elements disposed in the casing and arranged to cause the fluid introduced through the inlet to travel in a sinuous path and to be delivered into the lower part of the casing, and a tubular member connected to and projecting laterally from said lower part of the casing so as to form an outlet duct for the fluid, said member having formed therein a plurality of relatively staggered openings, said openings being inclined toward the casing and adapted to discharge the fluid in a diffused condition.
6. A blow-off muffler comprising a casing adapted to extend vertically and having a fluid inlet in the upper part thereof, coacting muffling elements disposed in the casing and arranged to cause the fluid introduced through the inlet to travel in a sinuous path and to be delivered into the lower part of the casing, and a tubular member connected to and projecting laterally from said lower part of the casing so as to form an outlet duct for the fluid, said member having formed therein a plurality of discharge openings and embodying deflectors for directing the fluid through said openings.
